DESIGN FOR AN ELECTRIC WIRE BURNING SET

Earl D. Boisselier, Glen Ellyn, Ill., assignor to
Blanche F. Boisselier, Glen Ellyn, Ill.

Application September 6, 1939, Serial No. 87,072

Term of patent 3½ years

To all whom it may concern:

Be it known that I, Earl D. Boisselier, a citizen of the United States, residing at Glen Ellyn, in the county of Du Page and State of Illinois, have invented a new, original, and ornamental Design for an Electric Wire Burning set, of which the following is a specification, reference being had to the accompanying drawing, forming part thereof.

The side of the device opposite that shown in

the drawing presents the same appearance as that shown, except that the switch device appearing on the transformer casing is absent.

The figure is a perspective view of an electric wire burning set showing my new design.

I claim:

The ornamental design for an electric wire burning set, as shown and described.

EARL D. BOISSELIER.
